UNITED STATES PATENT OFFICE.

JOHN L. MENCH, OF ROCHESTER, NEW YORK, ASSIGNOR TO DUFFY-POWERS COMPANY, INC., OF ROCHESTER, NEW YORK, A CORPORATION OF NEW YORK.

TAG AND HOLDER.

1,276,244.

Specification of Letters Patent. Patented Aug. 20, 1918.

Application filed January 21, 1918. Serial No. 212,881.

To all whom it may concern:

Be it known that I, JOHN L. MENCH, of Rochester, in the county of Monroe and State of New York, have invented certain 5 Improvements in Tags and Holders; and I do hereby declare the following to be a full, clear, and exact description of the same, reference being had to the accompanying drawings, forming a part of this specification, 10 and to the reference-numerals marked thereon.

This invention relates to tags and holders therefor, adapted for attachment to goods or merchandise, or to an adjacent support, to 15 indicate for instance the price at which the goods are to be sold.

The invention has for its object to provide an inexpensive and very durable device of this character having a detachable indicating disk or plate which may effectively display the selling price of the goods, and cannot be accidentally detached from its holder, or blown therefrom if used out of doors, and may readily be substituted by another disk 25 or plate bearing a different mark without removing the holder from the goods or from an adjacent support to which the holder may be attached. To these and other ends the invention consists in certain improvements 30 and combinations of parts, all as will be hereinafter more fully described, the novel features being pointed out in the claims at the end of the specification.

In the drawings which represent a preferred embodiment of this invention:

Figure 1 is a front elevation of one of the improved tags as sustained by a support presumably near the goods to be sold;

Fig. 2 is a rear top perspective view of the tag disk in normal position upon its holder, the upper portion of which is broken away;

Fig. 3 is a front elevation of the parts shown in Fig. 1, with the disk raised through the first step of its movement necessary to 45 detach it from the holder;

Fig. 4 is a front view indicating by full and dotted lines further steps of movement of the disk necessary to free it from the holder, and

Fig. 5 is a detail sectional plan view specially showing the lower apertured and notched lip on the disk or plate.

Similar reference numerals in the several figures indicate the same parts.

In its preferred form, the tag proper com-

prises a sheet metal disk or plate 1, bearing on its front face any desired mark, that shown being 10¢. Said disk 1 is shown as formed with two diametrically disposed rearwardly pressed integral marginal lips or lugs 2, 3, the lip 2 having an aperture 4, and the lip 3 having a like aperture 5 and also an adjacent open notch or slot 6. The tag holder comprises a stem 7 formed of a metal rod or wire bent to provide at its lower end an open and preferably elongated loop 8, the parallel limbs of which are about as long as the diameter of the disk 1, so that when this disk is normally adjusted on the stem, as shown in Fig. 1, the holder loop 8 is concealed behind the disk. When the disk 1 is thus normally adjusted on the holder the loop limb 9 is within the aperture 5 of the disk lip 3, and the opposite side portion of the stem loop 8 stands within the lip notch 6, as shown in Fig. 2. The disk lip apertures 4, 5, and the notch 6, loosely fit upon the holder stem and the loop limbs along which the disk lips 2, 3, may slide freely when applying the disk to the holder or removing it therefrom, as hereinafter more fully described. Any approved means may be adopted for supporting the tag holder upon or near the goods to be marked, the means shown being an eye 10 on the holder stem 7 engaging a screw-eye 11 fastened in a shelf 12 upon which the goods may be placed, or this part 12 may be a bar from which the goods may be hung, or the tag may be fastened by a cord passed through its eye 10, and around a part of any article to be sold for instance at the price the tag indicates.

It will be noticed that when the disk 1 is normally adjusted on the holder loop 8, as shown in Fig. 1, the opposite limbs of said loop next its bend respectively engage the aperture 5 and the notch 6 of the disk lip 3, and thus prevent the disk turning horizontally at the aperture 4 of its lip 2 upon the holder stem 7. The disk is thus always held with its front face squarely in view to most advantageously display the mark thereon. Furthermore, this engagement of the disk with the holder stem makes it practically impossible or quite difficult to accidentally detach the disk 1 from its holder by contact with other objects, and prevents blowing of the disk from the holder if used out of doors. The construction also makes it quite easy

to substitute another disk for the disk last used, all of the disks being interchangeable upon the same holder. To make such substitution, the disk 1 will first be raised on the 5 stem 7 from the normal position of Figs. 1 and 2 to that of Fig. 3, or until the disk lip 3 escapes from the holder loop limb 9, and the disk is then turned about one quarter around counterclockwise, and after its lip 10 notch 6 is swung aside clear of the holder stem 7, as shown in full lines in Fig. 4, the now turned and somewhat inclined disk indicated by the dotted lines at 10°, in Fig. 4, is slipped downwardly with its lip 2 along the 15 stem 7, thence to and around the bend of the loop 8 and then upwardly along the outer loop limb 9, as indicated by the dotted lines at 10°, and until said lip escapes from the limb 9 to entirely free the disk from the 20 holder. Another disk having a different mark will now be placed with the aperture 4 of its lip 2 upon the loop limb 9, and slipped downwardly thereon and thence around the loop bend and upwardly along the opposite 25 limb of the loop 8 and the aligned holder stem 7 until the lower disk lip 3 is above the end of the loop bend 9, and then the disk will be moved laterally to engage the notch 6 of its lip 3 with the holder stem 7. The disk is 30 then turned one quarter around clockwise and lowered until the aperture 5 of its lip 3 engages the loop limb 9, and the disk is then slipped downwardly upon both limbs of the holder loop 8 until its lip 3 stops at the 35 bend of said loop to retain the disk in the normal position of use shown in Figs. 1 and 2 of the drawings.

I claim as my invention:

1. A tag and holder comprising a holder 40 having at one end of its stem an open loop, and a detachable indicating disk or plate provided at one portion with an aperture

loosely fitting the holder stem and having at another portion a like aperture loosely fitting one limb of the holder loop and an adjacent notch or open slot loosely engaging the opposite limb of said loop when the disk or plate is normally adjusted on the holder. 45

2. A tag and holder comprising a holder having at one end of its stem an open loop, 50 and a detachable indicating disk or plate provided with opposed laterally projecting lips, one lip having an aperture loosely fitting the holder stem and the other lip having a like aperture loosely fitting one limb of the holder loop and also having an adjacent notch or open slot loosely receiving the opposite limb of said loop when the disk or plate is normally adjusted on the holder. 55

3. A tag and holder comprising a holder 60 having at one end of its stem an open loop, and a detachable indicating disk or plate provided with opposed laterally projecting lips, one lip having an aperture loosely fitting the holder stem and the other lip 65 having a like aperture loosely fitting one limb of the holder loop and also having an adjacent notch or open slot loosely receiving the opposite limb of said loop when the disk or plate is normally adjusted on the holder, 70 said holder loop having a length approximating the height of the indicating disk or plate to be mainly concealed thereby when the tag is in use.

4. In a tag, the indicating disk or plate 75 having opposed laterally projecting lips, one lip having an aperture adapted to receive a holder stem and the other lip having a like aperture adapted to loosely engage one limb of a loop on the holder and also having an adjacent notch or open slot adapted to receive the opposite limb of said holder loop. 80

JOHN L. MENCH.
